[57] CLAIM

The ornamental design for an electronic bookreader, as shown and described.

DESCRIPTION

FIG. 1 is a perspective view of the bookreader;

FIG. 2 is a top plan view of the bookreader;

FIG. 3 is a rear plan view of the bookreader;

FIG. 4 is a right side view of the bookreader;

FIG. 5 is a left side view of the bookreader;

FIG. 6 is a top end view of the bookreader; and,

FIG. 7 is a bottom view of the bookreader.

The broken line showing of conventional indicia is for illustrative purposes only and forms no part of the claimed design.

FIG. 1

FIG. 2

FIG. 3

FIG. 4

FIG. 5

FIG. 6

FIG. 7
